[57] **CLAIM**

The ornamental design for a cart, substantially as shown.

DESCRIPTION

FIG. 1 is a perspective view of a cart showing our new design, it being understood that the broken lines are for illustrative purposes only;

FIG. 2 is a side elevational view thereof to an enlarged scale; and

FIG. 3 is a front elevational view thereof to an enlarged scale.

Fig. 1.

*Fig. 2.**Fig. 3.*
